Robert Beale and Moses Bucklin
Gutter Patent

The Schedule referred to in these Gutter Patent-making, part of the same containing a description in the words of the said Robert Beale and Moses Bucklin themselves of their improvement in the construction of a Machine for slitting timber viz laths & boards for various uses required in building houses, fences &c &c.

To all whom these presents shall come. Now known that Robert Beale of Washington County District of Columbia & Moses Bucklin of the County of Crafton State of New Hampshire have invented a new and useful improvement in the construction of a machine for slitting timber viz laths boards, for various uses required in building houses fences &c &c and that the following is a full & exact description thereof: viz circular edges are prepared about 4 inches diameter one or more pairs to every split which is to be made running the board once through these edges are to be fixed on shafts which should be horizontal one above the other and the cutters are to be so fixed that the edges will one run true with the other: that is the pair one of each is to ^{be} fixed one on one shaft and one on the other shaft and the edges to come together running as there be all should graze and an edge to edge throughout and should be set such distance apart as the stuff is required to be split these shafts should be supported in certain frames or blocks and for splitting laths the stuff should first be sawed into plank about 1/4 inch thick then run through these cutters which are only the thickness of the laths apart and sufficient in number to let the whole board in to laths one going through. The shafts to be grazed one with the other are propelled by steam, water or any other power - it is preferable to have two sets of cutters one set running before the other. the first or forward cutters to set a little apart making an impression for those behind to follow and finish - in all cases there should be cutters between, the cutters and should fill between them as near as possible to the edges as the thickness

7590 L X

Markings of the plank with a minimum in one direction of seven
feet so as to give a bearing on the masts to support the
raft and keep them from sagging. for lifting out stuff for doors,
windows, partitions and floors it may be done by having a saw-horse
of the stuff and a set of long braces. What we principally claim is
laying one circular cutter over the other so as to prevent the plank
from shifting & spelling at the bottom and the application to making
rafts.
